MACHINE FOR DRILLING AND STUDDING
BRUSHES

Adolf Walther, Oberentfelden, Switzerland

Application November 1, 1948, Serial No. 57,696
In Switzerland November 1, 1947

3 Claims. (Cl. 300—3)

1

My present invention relates to improvements in machines for drilling and studding brushes, in which the brush carrier and a jig are disposed universally movable and so interconnected as to always be parallel to each other, the drilling and studding tools being operated in successive operations at the points of the brush defined by a hole-finder feeling-element and the said jig.

Machines are known in the art, in which the operative normally guides the jig manually and which, therefore, are called semi-automatics. Automatically operating machines, however, are known in the art, which control is effected through cams. Such latter machines, however, have the disadvantage to admit of only one brush pattern through a given set of cams. For each brush pattern, therefore, special cams have to be manufactured, the costs of which are comparatively great.

In accord with my present invention, the jig is operatively connected to pattern chain means which so co-act with two rows of control elements of the said means that one of said rows defines the horizontal, and the other the vertical motion of the jig.

One form of my present invention is shown in the accompanying drawing, in which—

Fig. 1 shows a side view of a brush-making machine,

Fig. 2 a top plan view of Fig. 1 in larger scale,

Fig. 3 a front view of a part of Fig. 1,

Fig. 4 a plan view on the line IV—IV of Fig. 3,

Fig. 5 a partial view of Fig. 3, partly in section,

Fig. 6 a partial view on the line VI—VI of Fig. 5,

Fig. 7 a section on the line VII—VII of Fig. 5,

Fig. 8 a section on the line VIII—VIII of Fig. 6,

Fig. 9 a partial view of a Geneva motion,

Fig. 10 a section, corresponding to Fig. 8, of a modified form of invention,

Fig. 11 a cross-section of Fig. 10,

Fig. 12 a partial section of a modified form of pattern chain means, and

Fig. 13 a partial top plan view of the chain means of Fig. 12.

The machine, as shown in Fig. 1, comprises a front main standard 1 and a rear standard 2. A hole-finder feeler pin 3, a drill 4 for drilling holes in a brush back, and a studding or punching tool 5 for inserting the bristles in the said holes are displaceably arranged on the main standard 1.

A slide 6 (Fig. 1) is mounted horizontally displaceable on the rear standard 2. Two plates 8

are attached to a lower angle iron 7 secured to the slide 6, and two similar plates 9 (Fig. 4) mounted vertically above the plates 8 are rigidly connected to the latter. A body 10, pivoted on a pin 11, is disposed between each plate 8 and its appurtenant plate 9. The two plates 8, 9 are provided with a row of holes 12 in which the pin 11 may be inserted as desired so as to locate the body 10 further in front or in rear. A carrier plate 13 is horizontally pivoted to each body 10; in that two rearwardly extending arms 14 of the plate 13 comprise a row of holes 15 each and a screw bolt 16 passes through one of said holes and is secured in the body 10. A propping stirrup 18 is articulated on screw bolts 18 to each plate 13, and its lower center portion is bent off forwardly at right angles and carries a pin 19. The two pins 19 of the two stirrups 18 are mounted in bosses 20 of a transom 21, to the center of which a connecting stirrup 22 is attached. At the head of the latter, a boss 23 is provided, in which a pin 24 is mounted. A third stirrup 18 is pivoted on the pin 24 and articulated to a third carrier plate 13 which in turn is articulated to a third body 10 disposed between two plates 25, 26 (Fig. 1). The lower of these latter plates, 25, is secured to an angle iron 27 which in turn is attached to the slide 6. The upper plate 26 carries a pin 28 which is engaged by one end of a resilient tension element 29 running over a guide roller 30. A weight 31, guided vertically movable is connected to the other end of the element 29 and is provided with a skew face 32. A roller 33, engageable with the latter, is pivoted to one arm 34 of a two-arm lever 34/35 pivoted on a pin 36. An actuating rod 37 engages the other arm, 35, of the said lever.

A hoop 38 is attached to the stirrup 22 and comprises a lug 39 to which a rod 40 is secured. The latter is mounted in a lever-arm 41 which in turn is pivoted to the upper end of a link 42. The lower end of the latter is articulated to one arm 43 of a two-arm lever 43/44, the other end of which carries a counterweight 45 (Fig. 1).

As seen from Fig. 3, three carrier plates 13 are so interconnected and arranged—in the manner described—as to be universally movable, all three plates being always parallel to each other. A jig 46 is secured to the top plate 13, with which the hole-finder feeler pin 3 cooperates. A brush stock 47, 48 each is secured to the two lower plates 13, the drill 4 co-acting with the right-hand stock 47, and the punch 5 with the left-hand stock 48.

The portion of the machine thus far described is known in the art, the jig 46 usually being manually guided so that the feeler pin 3 may successively engage the holes of the jig. The brush stocks 47, 48 are accordingly moved through the operative connection described, and holes may be drilled therein by means of the drill 4 and bristles be inserted in the holes by means of the punch 5.

My invention aims to automatically control the movements of the jig 46 and the brush stocks 47, 48 by means of the machine portion described below.

A second stirrup 49 is rotatably mounted on the pins 17 mounting the stirrup 18 on the plate 13 which carries the jig 46. A ball-and-socket joint, comprising a socket 50 and a ball 51, is disposed in the center of the stirrup 49, the said ball being disposed at the lower end of an actuating rod 52. The latter is so connected to a lever arm 55, by means of pins 54 engaged in slots 53 thereof, that the rod may be displaced in the longitudinal direction of the arm 55, but follows the rotation of the latter. The said arm 55 is pivoted on an axle pin 56 (Fig. 6) and is slotted at 57 to engage a pin 59 mounted on a horizontally displaceable rail 58. A screw bolt 60 is secured to the actuating rod 52 and engaged in a slot 61 of a bell-crank lever 62, 63 pivoted on a pin 64. The two pins 56, 64 are secured to a transom 65 by means of a nut 66. The arm 62 of the lever 62, 63 is bent, as shown in Fig. 2, and a slot 67 is provided on the arm 63. A pin 69 secured to a horizontally displaceable rail 68, is engaged in the slot 67.

The two rails 58, 68 are guided in lateral plates 70 of a frame 71 mounted on the standard 2. A guide element 72 is secured to the rail 58, comprising guide faces 73. Another guide element 74 having guide faces 75 is secured to the rail 68. Two rows of rollers 76, 77 co-act with the said faces 73, 74 and are pivoted on pins 78 to lamellae or slats 79. The latter at both ends are interconnected, as shown in Figs. 2 and 5, by chain links 80 which are engaged, on the front side of the machine, by two sprocket wheels 82, 83 keyed to a shaft 81 and comprising two rows of teeth each. The shaft 81 is mounted in ball bearings 84 in the frame 71, and a wheel 85 of a Geneva motion is rigidly secured to the sprocket wheel 83. A disc 86 (Figs. 5, 9) co-acting with the wheel 85 is provided with a semi-circular pin 87 and an eccentric pin 88, and is mounted on a driving shaft 89. The latter is driven from a driving disc 91 through a sprocket 90. The pattern chain, comprising the lamellae 79 and the links 80, is guided on the machine rear side by idling sprocket wheels 92.

At each revolution of the driving disc 91 and, therefore, of the disc 86, the wheel 85 of the Geneva motion is rotated through one tooth space, and the pattern chain thus moved through one lamellae division. During such movement, the two rails 58 and 68 are slightly displaced laterally through the action of the rollers 76, 77 on the guide faces 73, 75. Such displacement is transmitted through the lever arm 55 and the bell-crank 63 on to the actuating rod 52. The latter, through the ball-and-socket joint 50, 51 and the stirrup 49, moves the jig carrier-plate 13 so that the hole-finder feeler pin 3 at each succeeding operation is engaged in an adjacent hole of the jig 46. Holes then are drilled in the brush stock 47 by means of the drill 4 in accord with the jig and in a manner known per

se; and bristles are inserted in the brush stock 48 by means of the punch 5. The jig 46 is moved horizontally by the rollers 76, and vertically by the rollers 77. By combining the action of the two sets of rollers 76, 77 a diagonal movement of the jig may be produced also.

In Figs. 10, 11 a modified form of the guide element 74 of Fig. 8 is shown. Two members 95, having guide faces 75, are pivoted to a securing element 93 which is mounted on the rail 68 by means of screws 94, and leaf springs 96 act upon the said members 95. The latter are capable of yielding resiliently when the rollers 77 are engaged on the guide faces 75, and then are restored into their initial position through spring action. The guide element 72 may be adapted in a similar manner. In this way, the occurrence of shocks in the transmitting mechanism may be prevented.

In Figs. 12 and 13, another form of pattern chain is shown, in which the pivot pins 78 for the rollers 77 are fixed to slats or elements 97 which are provided with hinges and interconnected by means of pins 98. By replacing any of the chain elements 97, the pattern may be changed without the need of demounting the chain and mounting another pattern chain. Such pattern chain runs on correspondingly formed sprocket wheels 99 as shown in Fig. 12.

Existing semi-automatic machines may be converted into fully automatic machines by mounting thereonto the means described for moving the jig.

What I claim as new and desire to secure by Letters Patent, is:

1. In a mechanism for brush-making machines for automatically controlling the horizontal and vertical movements of a carrier for the jig and the associated brush backs relatively to a hole-finder feeler and to a drilling and studding tool each associated with said feeler, the improvement defined by the provision of a pattern chain comprising a plurality of slats interconnected at their ends by means of links, two rollers pivoted on studs secured in upright position to each slat, two superposed independent plates disposed in close proximity to said chain and mounted longitudinally displaceably in the machine frame, the said plates each having a cam means fixed thereto for engaging one or the other respectively of the said rollers, and means secured at one end to each of said plates respectively and at the other end to said carrier for continuously moving the latter in a horizontal and vertical direction respectively in correspondence with said pattern so as to bring the hole-finder feeler successively into engagement with the holes in the jig and thus also the drilling and studding tools with their respective brush backs.

2. In a mechanism for brush-making machines for automatically controlling the horizontal and vertical movements of a carrier for the jig and the associated brush backs relatively to a hole-finder feeler and to a drilling tool and to a studding tool, the said two tools being associated with said feeler, the improvement defined by the provision of a pattern chain comprising a plurality of slats exchangeably interlinked by means of hinged portions and pins interengaging the latter, a first pair of power-driven sprocket wheels rotatably mounted in the machine frame for engaging the said hinged portions, a second pair of sprocket wheels idly engaging the said portions, Geneva gear means for imparting a step-

by-step motion to said first pair of sprocket wheels and said chain, two rollers pivoted to each slat in upright position, a first and a second plate mounted for independent longitudinal movement in the machine frame and having a cam means each secured thereto, the cam means on the first flat being adapted to engage one, and the cam means on the second plate being adapted to engage the other of said rollers on each plate, first lever means for transmitting the movement of the first plate onto said carrier in a horizontal sense, and second lever means for transmitting the movement of the second plate onto said carrier in a vertical sense; the whole in such combination that the carrier is intermittently movable in a plane substantially normal to the plane of the pattern chain for the purpose described.

3. In a mechanism for brush-making machines for automatically controlling the horizontal and vertical movements of a carrier for the jig and the associated brush backs relatively to a hole-finder feeler and to a drilling tool and to a studing tool, the said two tools being associated with said feeler, the improvement defined by the provision of a pattern chain made of a plurality of interlinked slats revolvably mounted on the machine frame, two spaced rollers pivoted in upright position to each of said slats, the said rollers forming two spaced rows around the entire pattern chain, power-driven means for imparting a step-by-step movement to said chain, two superposed independent plates mounted longitudinally displaceably in the machine frame, each said plate having a cam means secured thereto

and adapted to be engaged by the consecutive rollers of said two rows respectively, one of said plates being operatively connected to an arm pivoted to the machine frame to impart an oscillating movement to said arm, a vertical rod connected at its foot end to said carrier by means of a ball-and-socket joint, the said rod being secured to said arm in longitudinally movable relation, a bell crank pivoted to the machine frame and at one end operatively connected to the head end of said rod, the other of said plates being operatively connected to the other end of said bell crank for the purpose of oscillating the latter so as to raise and lower the said rod and carrier 10 while they are oscillated through the reciprocating movement of the first flat so as to move the carrier in all directions in a plane substantially at right angles to the plane of the pattern chain in accordance with the pattern defined by 15 20 said two rows of rollers.

ADOLF WALTHER.
